Lemaire Patent Law Firm, P.L.L.C.(57) **CLAIM**

The ornamental design for a hanger, as shown and described.

DESCRIPTION

FIG. 1 is a first side view of a hanger showing the new design;

FIG. 2 is a second side view thereof;

FIG. 3 is a front view thereof;

FIG. 4 is a top view thereof; and,

FIG. 5 is a perspective view thereof.

In FIGS. 1-5, the relatively thin shade lines on the surface portions indicate contour, and not surface decoration. The broken lines are for the purpose of illustrating portions of the hanger that are not part of the claimed design.
